UNITED STATES PATENT OFFICE.

HERBERT H. PIPER, OF JACKSON, MISSOURI.

RAILWAY-CAR CUSPIDOR.

No. 805,995.

Specification of Letters Patent.

Patented Nov. 28, 1905.

Application filed June 15, 1905. Serial No. 265,419.

To all whom it may concern:

Be it known that I, HERBERT H. PIPER, a citizen of the United States, and a resident of Jackson, Missouri, have invented certain new and useful Improvements in Railway-Car Cuspidors, of which the following is a specification containing a full, clear, and exact description, reference being had to the accompanying drawings, forming a part hereof.

10 My invention relates to a railway-car cuspidor; and the object of my invention is to arrange a housing beneath each seat of a coach and provide the same with a series of cuspidors, and to provide drains for all of said 15 cuspidors and to locate suitable disinfectant tubes in each housing.

My invention consists in certain new and novel features of construction and arrangement of parts, that will be hereinafter more 20 fully set forth, pointed out in the claims, and illustrated in the accompanying drawings, in which—

Figure 1 is a longitudinal section through the center of a portion of a railway-coach or 25 street-car and showing my invention applied to said car. Fig. 2 is a plan view of the casing that is positioned beneath each seat and in which is arranged the drawers or boxes that are utilized as cuspidors. Fig. 3 is a 30 transverse section taken approximately on the line 3 3 of Fig. 2. Fig. 4 is a longitudinal section taken on the line 4 4 of Fig. 2. Fig. 5 is a transverse section taken on the line 5 5 of Fig. 2. Fig. 6 is a perspective view of one 35 of the drawers or boxes that is utilized as a cuspidor. Fig. 7 is an enlarged transverse section taken on the line 7 7 of Fig. 4 and showing the drawer or box withdrawn in dotted lines.

40 Referring by numerals to the accompanying drawings, 1 1 indicate the seat-frames, the same being supported in the usual manner by the legs 2. These seat-frames are provided with the inwardly-projecting flanges 3, which 45 support the outwardly-projecting flanges 4, formed on the top edges of the side and end walls of the casing 5 of my improved device. This casing is preferably constructed of sheet metal and comprises the end chambers 6, which 50 occupy transverse positions at the ends of the car-seat, and these end chambers are joined by the longitudinally-extending chamber 7. Formed integral with and projecting laterally

from the center of the chamber 7 are the rectangular pockets 8. Formed in the bottom 55 of each chamber 6 is a longitudinally-extending gutter 9, that is deepest at the center, so that the drainage through said gutters will be toward the centers of the chambers 6, and leading from the centers of these gutters to 60 the center of the chamber 7 and formed in the bottom thereof are the gutters 10, that are deepest at the center of said chamber 7 and there communicate with a discharge-opening 11, from which leads downwardly a discharge- 65 pipe 12. All of the pipes 12 lead downwardly through the floor of the car and are connected to a single drain-pipe 13, that runs the entire length of the car and is provided at one end with a catch-basin 14, closed at the bottom by 70 a hinged plate 15.

All of the matter deposited in the cuspidors will pass from the discharge-pipes 12 into the pipe 13 and finally into the catch-basin 14, and at the end of the run or at any suitable 75 point the contents of the catch-basin may be discharged by opening the lower end thereof.

Arranged to slide in each end of each chamber 6 is a rectangular drawer or open-topped box 16, the inner end thereof being open, and 80 formed in the bottom of each box is a gutter 17, the inner end of which is the lowest in order that matter deposited in the box will travel therethrough and discharge from the open end into the gutters 9. 85

Retractile coil-springs 18 are secured to the inner ends of the boxes 16 adjacent their sides, the opposite ends of which springs are secured to the bottoms of the chambers 6. These coil-springs normally hold the drawers or boxes 90 16 in their innermost positions and also prevent any rattling of said boxes in the chambers 6.

Formed in the outer side wall of each drawer or box is a longitudinally-extending groove 95 19, and in the front end of each groove is pivotally held between a pairs of ears 20 a rod 21, that extends rearwardly through the groove and is provided with a tooth 22 upon its rear end. Interposed between the rear 100 end of this arm and the side wall of the drawer or box 16 is an expansive coil-spring 23. The front end of the arm 21 is bent at right angles to the main body portion thereof and extends half-way across the front of the drawer 105 or box 16, as indicated by 23^a, and is pro-

vided on its end with a finger-hold 24. Adjacent this finger-hold 24 and secured to the front of the box or drawer 16 is an oppositely-arranged finger-hold 25. Formed in 5 the outer side walls of each of the compartments 6 are longitudinally-extending grooves 26, occupying the same planes as do the grooves 19, and in each of said grooves 26 is located ratchet-plate 27, the teeth of which are in opposition to the tooth 22 on the end of the arm 21.

Located in each pocket 8 is a suitable disinfectant-box 28, and leading therefrom inwardly toward the gutters 10 are the discharge-spouts 29. The tube 30 discharges 15 into the compartment 6 nearest the side of the car, and said pipe 30 is connected to a flushing-pipe 31, that extends along the side of the car between the walls thereof and which 20 may be connected at one end to a suitable source of water-supply.

When it is desired to make use of my improved cuspidor, the finger-holds 24 and 25 are engaged by the thumb and finger, and by 25 so doing the arm 21 is swung upon its pivot-point and the end thereof carrying the tooth 22 is moved backwardly and into the groove 19, out of the way of the teeth of the ratchet-plate 27, and by so doing compressing the 30 coil-spring 23. The drawer or box 16 is now pulled outwardly against the action of its retractile coil-springs 18, and when said drawer or box has been pulled outwardly a sufficient 35 distance the pressure of the thumb and forefinger upon the finger-holds 24 and 25 is released, and as a result the expansive coil-spring 23 will force the arm outwardly and carry the tooth 22 on the end of the arm 21 into one of the notches between the teeth and 40 the ratchet-plate 27, and thus a drawer or box will be held outwardly against the pull of the retractile coil-springs 18. The cuspidor is now in a position to be used, and all matter deposited into the drawer or box 16 will pass 45 downwardly through the gutter 17 therein and discharge therefrom into the gutter 9. When it is desired to close the cuspidor or allow the drawer or box to return to its normal position, the finger-holds 24 and 25 are 50 manually engaged, and as a result the tooth 22 is disengaged from between the tooth of the ratchet-plate 27, and the power stored in the coil-springs 18 will now act to pull the drawer or box inwardly to its normal position. The matter deposited in the gutters 9 will travel therefrom downwardly through the 55 gutters 10 and finally discharge through the aperture 11, discharge-pipe 12, and finally into the pipe 13 and from thence into the 60 catch-basin 14. The disinfectant discharging from the spouts 29 will act in the usual manner upon the matter within the cuspidor and will destroy all odor and germs that might otherwise arise therefrom. When it is de-

sired to flush all of the cuspidors, water is 65 allowed to discharge from the pipe 31 through the pipes 30 and into all of the cuspidors. When it is desired to discharge the contents of the catch-basin—for instance, at the end of the run of the car—the plate 15, that closes the 70 lower end of said catch-basin, is unlocked and allowed to swing downwardly to allow the contents of said catch-basin to pass into a suitable receptacle.

An improved cuspidor for railway-coaches 75 and street-cars of my improved construction is simple, inexpensive, easily operated, and occupies an out-of-the-way place beneath each car-seat.

The receiving drawers or boxes of the cuspidor are normally hid from view, and all of said cuspidors are self-draining and can be very readily cleaned. All of the matter placed in the cuspidors is subjected to the action of a suitable disinfectant, and the entire apparatus provides a very sanitary attachment for 80 railway-coaches and street-cars.

I claim—

1. In a cuspidor for railway-coaches and street-cars, a casing, a discharge-pipe leading 90 therefrom; drawers arranged to slide in said casing, there being gutters formed in the bottoms of said drawers, and there being gutters formed in the bottom of the casing that gradually decline toward the discharge-opening, substantially as specified.

2. In a cuspidor for railway-coaches and street-cars, a casing adapted to be positioned beneath a car-seat, a series of drawers arranged to slide in said casing, means whereby 100 said drawers are held in a closed position, means whereby said drawers are held in an open position; a discharge-spout leading downwardly from the center of the casing, there being gutters formed in the bottom of the casing that decline toward said discharge-spout, and there being gutters formed in the bottoms of the drawers, and suitable disinfectant-tubes located in the casing adjacent the discharge-spout, substantially as specified.

3. In a railway-car cuspidor, a casing removably positioned in the frame of a car-seat, there being gutters formed in the bottom of the casing that gradually decline toward a discharge-opening, drawers arranged to slide in 115 said casing, there being gutters formed in the bottoms of said drawers to correspond with the gutters in the bottom of the casing, and retractile coil-springs secured to the drawers and to the casing for normally holding said 120 drawers in a closed position; substantially as specified.

4. In a railway-car cuspidor, a casing removably positioned in the frame of a car-seat, there being gutters formed in the bottom of 125 the casing that gradually decline toward a discharge-opening, drawers arranged to slide in said casing, there being gutters formed in the

bottoms of said drawers to correspond with the gutters in the bottom of the casing, retractile coil-springs secured to the drawers and to the casing for normally holding said 5 drawers in a closed position, and means whereby said drawers are held open; substantially as specified.

In testimony whereof I have signed my name to this specification in presence of two subscribing witnesses.

HERBERT H. PIPER.
